Philip L. Reh

UNITED STATES PATENT OFFICE.

LE ROY H. RAND, OF BROOKLYN, NEW YORK, ASSIGNOR TO BROOKLYN SHIELD & RUBBER COMPANY, OF BROOKLYN, NEW YORK, A CORPORATION OF NEW YORK.

GARMENT PROTECTOR.

Application filed January 12, 1923. Serial No. 612,216.

To all whom it may concern:

Be it known that I, LE ROY H. RAND, a citizen of the United States, and a resident of the borough of Brooklyn, in the county of 5 Kings, city and State of New York, have invented certain new and useful Improvements in Garment Protectors, of which the following is a specification, reference being made to the accompanying drawings, forming 10 a part thereof.

My invention relates more particularly to garment-protectors of the moisture-proof type which are adapted to be worn by infants as a protective covering for the customary absorbent diaper, these protectors being made in a side-seamed form of "baby-pants" having waist and leg openings inherently capable of expanding and then closing or contracting about the infant's 15 body to afford an effective closure and protection, and furthermore to prevent an egress of moisture as well as to be comfortable to the wearer.

The objects of my invention are, among 20 other things, to provide an article of this general character in which there is embodied means for automatically drawing up the middle portion of the pants between the leg openings so as to obviate the hanging down of the seat or "baggy" effect between the child's legs when the garment-protector is in use. Heretofore baby pants have been made with a plain seat and crotch portions, both in front and back, which caused bagging 25 between the legs and is commonly regarded as a serious defect in such baby pants; my present improvement remedies such faults by providing an automatic shirring or gather to hold up the otherwise baggy seat, while allowing for the usual expansion and the contraction for the garment as a whole when fitted and adjusted about the waist and legs of the child to cover the ordinary absorbent diaper.

These and other objects of my improvement will be hereinafter fully set forth and particularly pointed out in the appended claims.

Preferred embodiments of my invention 50 are shown in the accompanying drawings in which—

Fig. 1 is a front elevation view of a pair of baby pants embodying one form of my improvements;

Fig. 2 is a front elevation showing 55 another form;

Fig. 3 is an enlarged sectional view showing the gather or shirring reinforced by an elastic strip;

Fig. 4 is a perspective view showing the 60 strip partially covering the shirring in the crotch of the pants; and

Fig. 5 is a front elevation view with the reinforcing strip covering the shirring on 65 the outside of the pants.

Similar numerals refer to similar parts throughout the several figures.

Referring to the drawings and more particularly to Fig. 1, the improved protector is preferably formed of sheet rubber material or any water-proof fabric cut from a single sheet and preferably united by side-seams (not shown) between the waist opening 6 and the two leg openings 7 and 8, each opening being formed by the folded-over 70 hem of the front portion 9 and rear portion 10 and then secured by lines of stitching 11, whereby annular looped pockets are produced with shirring 12 about the peripheries 75 of the openings. Within each pocket is the usual elastic band (not shown), which produces the shirring 12 about each of the openings to allow of a ready distension of the garment when about to be placed about the body and legs of the wearer. In ordinary 80 forms of baby-pants the seat or crotch portion extends downwardly to the dot and dash line 13 shown in Fig. 1 which produces an undesirable bagging and fullness between 85 the leg openings 7 and 8.

To produce shirring or gather 14 in the sheet rubber substantially in the dividing line of the garment, as shown in Fig. 1, the plain sheet of material while the rubber is in its uncured condition is laid on a roll and then a plain elastic strip 15 (Fig. 3) is stretched and cemented or otherwise fastened to this uncured rubber causing same to gather or shirr with transverse corrugations as the elastic strip 15 is released and assumes its normal form. The rubber material is then vulcanized and the strip 15 may be removed as is shown in Fig. 1, or such strip may remain attached to cover and reinforce the shirring 14 either inside the garment as shown in Figs. 3 and 4, or outside as shown in Fig. 5.

In Fig. 2 I have shown the shirring 14 as

extending in the crotch of the pants only, and not extending to the waist opening 6 as illustrated in Figs. 1, 4 and 5. In Fig. 4 I have shown the strip 15 covering the shirring 14 only in the crotch while the exposed ends of the shirring extend to the hem of the waist opening 6.

In all these forms of construction this shirring 14, either with or without the aid 10 of the elastic strip 15, serves to advantageously gather or draw up the sheet rubber material between the legs of the child so that a snug fit is automatically produced in the seat to cover the underlying diaper, without 15 any bagging which produces discomfort in the child as well as an undesirable fullness in the pants rendering it likely to be torn or ripped if the child be playing upon the floor. My improvement therefore automatically 20 provides means for gathering up the fullness of the garment, particularly in the crotch, while allowing for the required expansion and contraction in placing the pants on the child.

25 The invention is not to be limited to the particular constructions shown, nor to any particular details whereby this desired gathered effect may be produced, as many changes and alterations may be made without departing from the principles of the invention and without sacrificing its advantages.

I claim as my invention:

1. A garment-protector comprising a body 35 formed of a single piece of elastic material having waist and leg openings with a seamless loose seat therebetween, and expandible and contractible means, comprising a single line of shirring extending from front 40 to back through the middle of the crotch and integral with the body, for normally gathering the looseness of the seat from both front and back in expandibly drawn-up position between the leg openings.
- 45 2. In a garment-protector formed with a single-pieced body of elastic material having waist and leg openings with a seamless loose seat therebetween, of a continuous line of shirring integral with said body and seat 50 and extending unbrokenly from opposite sides of the waist opening through the crotch

of the seat, and a strip of elastic material of substantially the same length as said shirring secured over said shirring whereby said shirring and said strip both act to normally 55 gather the baggy looseness of the seat in expandibly drawn-up position between the leg openings.

3. In a garment-protector formed with a single pieced body of elastic material hav- 60 ing waist and leg openings with a seamless loose seat therebetween, of a continuous line of shirring integral with said body and seat and extending unbrokenly from opposite sides of the waist opening through the 65 crotch of the seat, and a strip of elastic material of substantially the same length as said shirring secured over the inner face of said shirring whereby said shirring and said strip both act to normally gather the 70 baggy looseness of the seat in expandibly drawn-up position between the leg openings.

4. In a garment-protector formed with a single-pieced body of elastic material having 75 waist and leg openings with a seamless loose seat therebetween, of a continuous line of shirring integral with said body and seat and extending unbrokenly from opposite sides of the waist opening through the crotch of the seat, and a strip of elastic ma- 80 terial secured over one side of the crotch portion of said shirring below the waist opening whereby said shirring and said strip both act to normally gather the baggy looseness of the seat in expandibly drawn-up po- 85 sition between the leg openings.

5. In a garment protector formed with a single-pieced body of elastic waterproof ma- 90 terial having shirred waist and leg openings with a seamless loose seat therebetween, of a continuous vertical line of transverse shirring integral with said body and seat extending from opposite parts of the waist opening through the crotch of the seat, and a flat elastic strip secured over the shirring 95 throughout its length, said shirring and strip both acting in unison to normally and yieldingly gather from both front and back the looseness of the seat in expandibly drawn-up position between the leg openings.

LE ROY H. RAND.
